THREAD-ADVANCING REEL

Richard W. Stanley, Drexel Hill, and William B. Lowe, Chester, Pa., assignors to American Viscose Corporation, Wilmington, Del., a corporation of Delaware

Application October 29, 1943, Serial No. 508,174

23 Claims. (Cl. 28—71.7)

1

This invention relates to thread-advancing reels which may be used for the production of a yarn store which is continuously advanced axially of the periphery of the reel, during which time it may be subjected to fluid treatment in the manner and for the purposes conventional in the art.

It is a particular object of this invention to provide an improved thread-advancing reel. It is a further object of this invention to devise a reel which is adaptable to either a cantilever or double-end supported structure. It is a further object of the invention to provide a reel of this type based upon a structural principle which, when embodied in a reel of considerable axial length results in substantially uniform efficiency in thread-advancing action throughout the length of the reel, and, at the same time, is adapted to operation at high speeds of rotation of the reel. Further objects and advantages of the invention will be apparent from the drawings and description thereof hereinafter.

In the drawings illustrative of the invention—

Figure 1 is a mid-section taken axially half way through one embodiment of the reel of this invention;

Figure 1a is a view partly in section showing a modified mounting of the reel of Figure 1;

Figure 2 is a section taken on line II—II of Figure 1;

Figure 3 is a mid-section taken axially half way through another embodiment of the invention;

Figure 4 is a section taken on line IV—IV of Figure 3;

Figure 5 is a mid-section taken axially through another embodiment of the invention;

Figure 6 is a section taken on line VI—VI of Figure 5;

Figure 7 is a mid-section taken axially half way through a modified form of reel; and

Figure 8 is a section taken on line VIII—VIII of Figure 7.

In general, thread-storing, thread-advancing reels of this invention comprise a concentric set of spaced, longitudinally extending bars and an eccentric set of spaced, longitudinally extending bars interdigitating with and alternating between the bars of the first set. The bars in the non-concentric set are supported by a non-rigid and resiliently flexible mounting which allows axial displacement of the bars either individually or as associated groups with respect to the remaining bars in the set. This flexible mounting is

2

preferably of such a character that displacement of the bars from a given position of rest, which may advantageously be the mean axial position of these bars during operation of the reel, is opposed resiliently by the mounting, but, during actual operation of the reel, such resilient mounting acts not only to restore the bars to their "rest" or mean position when permitted to do so, but also tends to carry the bars beyond their "rest" or mean position by virtue of their kinetic energy stored therein at the time of passage through the "rest" or mean position and imparted by the motion resulting upon release of the resilient mounting from its position of displacement from "rest" or mean position.

Referring more particularly to the embodiment of Figures 1 and 2, the concentric set of longitudinally extending bar members 2 are constituted of a cylindrical-cage member having a flange 4 at one end and an annular member 3 at the other end thereof and being appropriately slotted longitudinally to leave spaces alternating between the bars 2 within which the bars 5 of the other set may be actuated. The cylindrical cage 2 may be clamped between end flanges or spiders 6 and 7 by suitable spaced cap screws 8. The system comprising the cylindrical cage and flanges 6 and 7 constitutes a housing which may have any axial length desired, and which may house the actuating mechanism for the other set of interdigitating bars 5. This housing is supported for rotation with respect to shaft 9 by means of suitable bearings 10 and 11. Flange 7 may be provided with a non-circular projection 12 which is adapted to fit in a corresponding socket 12' of a coupling 12 upon the shaft 12" which may be driven by the gear 12''' keyed thereto. Secured to the shaft 9 is a suitable non-circular projection 13 adapted to be received by a corresponding recess in a normally stationary but retractable supporting element 13' or by a coupling member 121x to a shaft 12''x as shown in Figure 1a (analogous to 121 and 12'') for driving it in a direction the same or opposite to that of projection 12. As the occasion may demand, rotation of shaft 9 provides a means of modifying the pitch of the helical path followed by the thread about the reel. Normally, shaft 9 is maintained stationary unless this pitch modification is found necessary. If shaft 9 is rotated at an equivalent speed but in the opposite direction as that of projection 12 the pitch will be twice that obtained when shaft 9 is held stationary. If shaft 9 is rotated at half the speed and in the same direction as projection 12 the

pitch obtained will be one half that obtained when shaft 9 is held stationary.

Two sleeves 14 and 15 are mounted upon the shaft 9 and are suitably spaced by the ring 16. The sleeves 14 and 15 have external cylindrical surfaces whose axes are askew and eccentric to the axis of shaft 9 but parallel to each other. Upon each of the sleeves, a resilient spider member 17 is mounted, preferably by means of ball bearings 18. These spiders 17 are of a resilient material, preferably of thin spring metal, and have individual radially extending members 19 between opposed pairs of which, the bars 5 are secured by suitable means, such as by the non-circular rod 20 embedded within inwardly-extending portions of the bars 5 and the nuts 21. Skew plates 22 and 23 are also carried by the bearings 18 and have outer flanged portions 24 which bear against the ends of the rods 20.

Where it is desired to protect the main operating parts from any possibility of clogging and corrosion when the reel is used for subjecting the filamentary material to liquids, a flexible sealing membrane 25, such as of rubber or synthetic rubber, may be secured to the outer portion of the resilient supporting means for the non-concentric bars and to the ends of the concentric cylindrical cage as shown.

As shown, the annular member 3 projects beyond the flange 6 and overhangs the outer rim of a stationary member 6', which is integral with or affixed to the support 13'. The outer peripheral surface of the member 6' preferably slopes inwardly from its outer rim to a generally cylindrical portion, which serves to hold any accumulation of thread formed after breakage of the thread being handled by the reel or during lacing up of the reel or any machine comprising the reel. Occasionally, stray filaments also tend to gather on this member 6'. The collecting member 6' has a surface of sufficient axial extent to provide adequate storage space and ready access for the operator to remove the accumulated filaments or threads at his convenience without danger of injury to his hands, and without the necessity either of stopping the reel or of giving it immediate attention when the above-mentioned emergencies arise.

In operation, the skew plate flanges 24 cause substantial axial motion of the bars 5, such motion being imparted individually to each of the bars 5 by virtue of the individual resilient projecting members 19. By virtue of the eccentricity of the resilient supporting means and the bars 5, the axial to and fro motion of the bars imparted by the skew plates is combined with a radial component of motion which alternately causes first the protrusion of the bars 5 outside the periphery of bars 2 and then their recession within that periphery, thereby resulting in the advancing of the thread axially of the reel.

Figures 3 and 4 show a modification in which reference numerals with the suffix letter *a* corresponds to the parts in Figures 1 and 2 designated by the corresponding numerals without the suffix. The parts correspond in function, but may not be identical in structure, as will be apparent from the description hereafter.

Shaft 9a has a portion having an eccentric cylindrical surface 16a' and another portion 14a' which has a concentric cylindrical surface and carries a sleeve 14a which has an eccentric cylindrical surface which is also askew with respect to the axis of shaft 9a. A flexible spider 17a is rotatably mounted on the surface 15a' of

the shaft, and has radially extending outer portions 19a which may carry one or more, and, as shown, carries three bars 5a as a unit. A skew plate formed of the web members 22a and 23a is carried by a ball bearing 18a upon the askew and eccentric sleeve 14a. Each segmental unit of three bars 5a is connected at one end by a yoke 26a having an overhanging portion 27a provided with a recess adapted to bear against ball 28a. Suitable bolts 20a and nuts 21a secure the yoke 26a, the group of bars 5a and the flexible spider 17a. Springs 20a are provided and tend to secure a firm bearing between the balls 28a and the recesses formed in the associated yokes 26a and the skew plate structure 22a and 23a.

Referring to Figures 5 and 6, an adaptation of the reel construction of the invention to a cantilever form of reel is shown. The concentric set of bar members 2b are formed by suitably slotting radially an integral cylindrical cage member 3b having an outwardly extending flange 4b. The member 3b is secured by cap screws 8b to the supporting flange 6b whose hub is secured and keyed to the end of the shaft 9b. The shaft is mounted for rotation within a stationary sleeve 30b suitably secured within a supporting bearing 31b. The end of the sleeve 30b adjacent the hub of flange 6b has a peripheral surface 14b which is eccentric and askew with respect to the axis of shaft 9b and carries a skew plate 22b on a ball bearing 18b. A bushing 32b is carried by an adjacent peripheral surface of the sleeve 30b, which surface is eccentric but not askew with respect to the axis of shaft 9b, the amount of eccentricity being substantially the same as that of the surface 14b.

A pair of spaced flexible and resilient spiders 17b fit about the bushing and are held in proper axial relation with respect thereto by suitable washers or rings, such as 16b. The flexible spiders are secured to either side of the inwardly extending portions of the movable bar members 5b by means of the bolts 20b and nuts 21b. Upon each of the bolts 20b is mounted a collar 33b which extends through an aperture 34b in the skew plate 22b. Between each of the collars 33b and the corresponding head of the bolt, there is a washer 35b against which a spring 36b is arranged to press, a pin 37b projecting from the head of the bolt 20b serving to guide the spring and to prevent its dislocation. A flexible sealing membrane 25b is arranged to protect the working parts against the entrance of corrosive or abrasive materials.

In operation, the reel of Figures 5 and 6 is similar to the others shown, the only difference being that the springs 36b serve to assure that the bolts 20b with their bar members 5b follow the movements of the skew plate 22b.

While the lengths of the reels shown in Figures 1 to 6 are of the same order of size as their diameter, the reels may be made of any length, regardless of their diameter. Figures 7 and 8 show a long reel similar in construction to the reel of Figure 1, and in these figures corresponding parts bear the same reference characters but with the addition of a postscript *c*. As shown in Figures 7 and 8, when reels whose length is many times the size of their diameter are desired, a larger number of flexible supporting members comprising the flexible spiders 17c may be provided along the reel to obtain adequate support for the bars 5c to prevent them from sagging in the middle from the tension loads imposed by the filamentary material wound thereon.

The bars 2c are further strengthened by the inwardly extending longitudinal U-shaped braces 41 through the bottom of which rods 20c extend. Also additional support for the cylindrical cage having bars 2c may be provided in the form of one or more rigid spiders 38 rotatably mounted upon intermediate portions of the shaft to support a corresponding annular member 39 secured to the inner periphery of the bars 2c. In addition, spaced rings 40 may be provided to stiffen the set of bars 2c in the cylindrical cage member.

From a consideration of the various embodiments disclosed, it will be readily apparent that by mounting the actuatable set of bar members upon flexible resilient spiders or webs, and on an axis which is eccentric to that of the concentric set of bar members, and imparting an axial or longitudinal component of motion to the actuatable bars by means of a skew plate which moves therewith, relative sliding motion between the various parts of the reel is reduced to a minimum. In addition, the repeated flexing from a mean position of the resilient mounting requires but little energy since the tendency of a flexed resilient member to return to original position generally carries the flexed member well beyond its unstressed position, so that but a small additional force is needed to complete the flexure to the full extent required by the cycle of operation of the reel. In this sense, the system is somewhat analogous to the action of the pendulum of a clock, except that a much greater advantage is obtained in the case of the flexible mounting when the reel is operated at high speeds, thereby increasing the frequency of flexing. The utmost advantage is obtained by designing the flexible members so that the portions thereof which undergo the repeated flexing have a natural period of vibration which is substantially identical with the period of flexure imposed thereon by the skew plate of the reel when operated at the particular speed desired.

The various parts of the reel may be made of any particular materials desired. The construction of Figures 1 to 4, 7 and 8, lends itself readily to making the cylindrical cage members 3, the bar members 5 and bar members 2 associated therewith of materials which offer the most satisfactory bearing surface for the filamentary material to be handled thereby from the standpoint of smoothness, durability, and/or resistance to corrosion under the influence of any liquids with which the filamentary material is to be treated while being advanced longitudinally of the reel, without making the remainder of the reel thereof. This is of tremendous importance from the viewpoint of initial and depreciation cost of such reels, since materials which best meet the requirements specified are generally considerably more expensive than related materials which would be fully adequate for all portions of the supporting structure of the reel other than those intended to contact the filamentary material. Thus, parts 2, 3, 4 and 5 may be made of porcelain, Durez, Alsimag, etc., while such other parts as 6 and 7 may be made of Bakelite, stainless steel, etc. These latter parts need not be made of materials which are entirely free of tendencies to be pitted or otherwise superficially altered by the combined action of corrosive chemicals and rubbing action of the filaments handled.

It is to be understood that changes and variations may be made without departing from the spirit and scope of the invention as defined in the appended claims.

We claim:

1. Reel mechanism comprising a set of spaced longitudinally extending bar members, means for rotatably mounting said set of bar members about an axis, a second set of spaced, longitudinally extending bar members interdigitating with the members of the first set, flexible and resilient means for supporting the second set rotatably about an axis offset with respect to the axis of rotation of the first set, and means for imparting to a selected part of the second set of bar members at predetermined intervals a substantially axial reciprocatory motion relative to the first set of bar members, said motion-imparting means comprising at least one member mounted for rotation with the bar members of the second set upon an axis askew to the axis of the bar members of the second set and arranged to co-operate with the bar members of the second set through rigid extensions connected thereto.
- 15 2. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto.
- 25 3. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto.
- 30 4. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and spring means for urging the bar members of the second set into engagement with the plate-like member.
- 35 5. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and spring means for urging the bar members of the second set into engagement with the plate-like member.
- 40 6. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and spring means for urging the bar members of the second set into engagement with the plate-like member.
- 45 7. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and ball and socket connections between the plate-like member and the rigid extensions connected to the bar members.
- 50 8. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and ball and socket connections between the plate-like member and the rigid extensions connected to the bar members.
- 55 9. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and ball and socket connections between the plate-like member and the rigid extensions connected to the bar members.
- 60 10. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and ball and socket connections between the plate-like member and the rigid extensions connected to the bar members.
- 65 11. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and ball and socket connections between the plate-like member and the rigid extensions connected to the bar members.
- 70 12. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and ball and socket connections between the plate-like member and the rigid extensions connected to the bar members.
- 75 13. Reel mechanism comprising a set of spaced, longitudinally extending bar members, means for rotatably mounting the set of bar members about an axis, a second set of spaced, longitudinally extending bar members interdigitating with the members of the first set, a stationary eccentric bearing means, at least one flexible and resilient web mounted on the eccentric bearing means, and carrying adjacent the periphery thereof the second set of bar members, a stationary bearing means askew to the stationary eccentric bearing means, a rigid plate-like member mounted for rotation on the skew bearing means and having a portion arranged to co-operate with the bar members of the second set through rigid extensions connected thereto, and ball and socket connections between the plate-like member and the rigid extensions connected to the bar members.

5. Reel mechanism comprising a set of spaced longitudinally extending bar members, means for rotatably mounting the set of bar members about an axis, a second set of spaced, longitudinally extending bar members interdigitating with the members of the first set, a stationary eccentric bearing means toward each end of the reel, said bearing means being also askew to the axis of rotation of the first set of bar members but having their axes substantially parallel to and offset with respect to each other, a flexible and resilient web rotatably mounted about the axis of each of said bearing means and carrying between portions adjacent the peripheries thereof the second set of bar members, a rigid plate-like member mounted for rotation on each of the eccentric and askew bearing means and having portions arranged to engage with the bar members of the second set through rigid extensions connected thereto.

6. A cantilever thread-advancing reel supported from one end only thereof comprising a rotatable shaft, a flange-like member secured and keyed to the shaft, a set of spaced, longitudinally extending bar members carried by the flange-like member concentric with the shaft, a stationary sleeve about the shaft having eccentric external bearing portions thereon, flexible and resilient supporting means rotatably mounted on one of the eccentric bearing portions of the sleeve, a second set of spaced, longitudinally extending bar members interdigitating with those of the first set and fixedly secured to an outer portion of the supporting means, and means mounted on said sleeve for controllably flexing the resilient supporting means for imparting to a selected part of the second set of bar members at predetermined intervals a substantially axial reciprocatory motion relative to the first set of bar members.

7. A cantilever thread-advancing reel supported from one end only thereof comprising a rotatable shaft, a flange-like member secured and keyed to the shaft, a set of spaced, longitudinally extending bar members carried by the flange-like member concentric with the shaft, a stationary sleeve about the shaft having eccentric external bearing portions thereon, flexible and resilient supporting means rotatably mounted on one of the eccentric bearing portions of the sleeve, a second set of spaced, longitudinally extending bar members interdigitating with those of the first set and supported on the supporting means, another portion of the eccentric bearing surface of the sleeve being arranged with its axis askew to the axis of the shaft, a rigid plate-like member mounted for rotation on the skew portion of the sleeve and having a portion arranged to co-operate with the bar members of the second set through rigid extensions connected thereto.

8. Reel mechanism comprising a shaft, a set of spaced longitudinally extending bar members mounted concentrically about the shaft for rotation with respect thereto, a second set of spaced longitudinally extending members interdigitating with the members of the first set, flexible and resilient means for supporting the second set rotatably about the shaft on an axis offset with respect to the center thereof, and means for imparting to a selected part of the second set of bar members at predetermined intervals a substantially axial reciprocatory motion relative to the first set of bar members, said motion-imparting means comprising at least one member mounted for rotation with the bar members of the second set upon an axis askew to the axis of

5 the bar members of the second set and arranged to co-operate with the bar members of the second set through rigid extensions connected thereto.

9. Reel mechanism comprising a shaft, a set of spaced longitudinally extending bar members mounted concentrically about the shaft for rotation with respect thereto, a second set of spaced longitudinally extending members interdigitating with the members of the first set, flexible and resilient means for supporting the second set rotatably about the shaft about an axis offset with respect to the center thereof, and means for imparting to a selected part of the second set of bar members at predetermined intervals a substantially axial reciprocatory motion relative to the first set of bar members, said means comprising at least one member mounted for rotation with the bar members of the second set upon an axis askew to the axis of the bar members of the second set and arranged to co-operate with the bar members of the second set through rigid extensions connected thereto, the bar members of the two sets being made of a material exerting substantially no appreciable detrimental influence upon the filamentary material being handled.

10. Reel mechanism comprising a set of spaced longitudinally extending bars, means for rotatably mounting said set of bars about an axis, a second set of spaced, longitudinally extending bars interdigitating with the bars of the first set, means comprising ball and socket connections for supporting the bars of the second set rotatably about an axis offset with respect to the axis of rotation of the first set.

11. Reel mechanism comprising a set of spaced longitudinally extending bars, means for rotatably mounting said set of bars about an axis, a second set of spaced, longitudinally extending bars interdigitating with the bars of the first set, at least one member mounted for rotation with the bars of the second set upon an axis eccentric and askew to the axis of the bars of the first set and arranged to control the bars of the second set through ball and socket connections therewith.

12. Reel mechanism comprising a set of spaced longitudinally extending bars, means for rotatably mounting said set of bars about an axis, a second set of spaced, longitudinally extending bars interdigitating with the bars of the first set, a member mounted for rotation with the bars of the second set upon an axis eccentric to that of the first set of bars, a second member mounted for rotation with the bars of the second set upon an axis inclined to the axis of the first rotatable member, the first member being so mounted and the two members being so connected to the bars of the second set that the first member follows the motion transmitted by the bars from the second member.

13. Reel mechanism comprising a set of spaced longitudinally extending bars, means for rotatably mounting said set of bars about an axis, a second set of spaced, longitudinally extending bars interdigitating with the bars of the first set, at least two rotatable members for supporting the bars of the second set, one of said members being mounted upon an axis eccentric to that of the first set of bars, another of said rotatable members being mounted for rotation upon an axis inclined to the axis of said first rotatable member, the construction and arrangement being such that the motion of the first-mentioned rotatable

member is controlled by the motion of the second-mentioned member through the interconnecting bars.

14. Reel mechanism comprising a set of spaced longitudinally extending bars, means for rotatably mounting said set of bars about an axis, a second set of spaced, longitudinally extending bars interdigitating with the bars of the first set, at least two rotatable members for supporting the bars of the second set, one of said members being flexibly resilient and being mounted upon an axis eccentric to that of the first set of bars, another of said rotatable members being mounted for rotation upon an axis inclined to the axis of said first rotatable member and universal connections between the bars of the second set and the rotatable members.

15. Reel mechanism comprising a set of spaced longitudinally extending bar members, means for rotatably mounting said set of bar members about an axis comprising two spaced supporting members substantially enclosing the space within said reel bars at each end thereof and thereby forming with the bars a rotatable cage-like housing, a second set of spaced, longitudinally extending bar members interdigitating with the members of the first set and having portions projecting inwardly of the cage-like housing, flexible and resilient means secured to the inwardly projecting portions and extending inwardly therefrom for supporting the second set rotatably about an axis offset with respect to the axis of rotation of the first set, said supporting means being so constructed and arranged as to permit with resilient opposition relative longitudinal reciprocatory motion among the bars of the second set, and sealing means, extending substantially the entire length of the space inside the cage-like housing and having intermediate portions secured to the inwardly projecting portions of the second set of bar members, for enclosing the flexible and resilient supporting means.

16. Reel mechanism comprising a set of spaced longitudinally extending bar members, means for rotatably mounting said set of bar members about an axis comprising two spaced supporting members substantially enclosing the space within said reel bars at each end thereof and thereby forming with the bars a rotatable cage-like housing, a second set of spaced, longitudinally extending bar members interdigitating with the members of the first set and having portions projecting inwardly of the cage-like housing, flexible and resilient means secured to the inwardly projecting portions and extending inwardly therefrom for supporting the second set rotatably about an axis offset with respect to the axis of rotation of the first set, means for controllably flexing the resilient supporting means for imparting to a selected part of the second set of bar members at predetermined intervals a substantially axial reciprocating motion relative to the first set of bar members, and flexible sealing means, extending substantially the entire length of the space inside the cage-like housing and having intermediate portions secured to the inwardly projecting portions of the second set of bar members, for enclosing the flexible and resilient supporting means and the motion-imparting means.

17. Reel mechanism comprising a set of spaced longitudinally extending bar members, means for rotatably mounting said set of bar members about an axis comprising two spaced supporting members substantially enclosing the space within said reel bars at each end thereof and thereby form-

ing with the bars a rotatable cage-like housing, a second set of spaced, longitudinally extending bar members interdigitating with the members of the first set and having portions projecting inwardly of the cage-like housing, flexible and resilient means secured to the inwardly projecting portions and extending inwardly therefrom for supporting the second set rotatably about an axis offset with respect to the axis of rotation of the first set, means for imparting to a selected part of the second set of bar members at predetermined intervals a substantially axial reciprocatory motion relative to the first set of bar members, said motion-imparting means comprising at least one member mounted for rotation with the bar members of the second set upon an axis askew to the axis of the bar members of the second set, and flexible sealing means, extending substantially the entire length of the space inside the cage-like housing and having intermediate portions secured to the inwardly projecting portions of the second set of bar members, for enclosing the flexible and resilient supporting means and the motion-imparting means.

18. Reel mechanism comprising a set of spaced longitudinally extending bar members, means for rotatably mounting said set of bar members about an axis comprising two spaced supporting members substantially enclosing the space within said reel bars at each end thereof and thereby forming with the bars a rotatable cage-like housing, a second set of spaced, longitudinally extending bar members interdigitating with the members of the first set and having portions projecting inwardly of the cage-like housing, flexible and resilient means secured to the inwardly projecting portions and extending inwardly therefrom for supporting the second set rotatably about an axis offset with respect to the axis of rotation of the first set, means for imparting to a selected part of the second set of bar members at predetermined intervals a substantially axial reciprocatory motion relative to the first set of bar members, said motion-imparting means comprising at least one member mounted for rotation with the bar members of the second set upon an axis askew to the axis of the bar members of the second set and arranged to co-operate with the bar members of the second set through rigid extensions from the inwardly projecting portions thereof, and flexible sealing means extending substantially the entire length of the space inside the cage-like housing and having intermediate portions secured to the inwardly projecting portions of the second set of bar members, for enclosing the flexible and resilient supporting means and the motion-imparting means.

19. Reel mechanism comprising a set of spaced, longitudinally extending bar members, means for rotatably mounting the set of bar members about an axis comprising two spaced supporting members substantially enclosing the space within said reel bars at each end thereof and thereby forming with the bars a rotatable cage-like housing, a second set of spaced, longitudinally extending bar members interdigitating with the members of the first set and having portions projecting inwardly of the cage-like housing, a stationary eccentric bearing means, at least one flexible and resilient web mounted on the eccentric bearing means and secured to the inwardly projecting portions and extending inwardly therefrom for carrying adjacent the periphery thereof the second set of bar members, a stationary bearing means askew to the stationary eccentric bearing means, a rigid

11

plate-like member mounted for rotation on the skew bearing means and having a portion arranged to co-operate with the bar members of the second set through rigid extensions from the inwardly projecting portions thereof, and flexible sealing means, extending substantially the entire length of the space inside the cage-like housing and having intermediate portions secured to the inwardly projecting portions of the second set of bar members, for enclosing the flexible and resilient supporting means and the motion-imparting means.

20. A cantilever thread-advancing reel supported from one end only thereof comprising a rotatable shaft, a flange-like member secured and keyed to the shaft, a set of spaced, longitudinally extending bar members carried by the flange-like member concentric with the shaft, a stationary sleeve about the shaft having eccentric external bearing portions thereon, flexible and resilient supporting means rotatably mounted on one of the eccentric bearing portions of the sleeve, a second set of spaced, longitudinally extending bar members interdigitating with those of the first set and each having an inwardly projecting portion fixedly secured to an outer portion of the supporting means, means mounted on said sleeve for controllably flexing the resilient supporting means for imparting to a selected part of the second set of bar members at predetermined intervals a substantially axial reciprocatory motion relative to the first set of bar members, and sealing means having its outer portion secured to the flange-like member and an intermediate portion secured to the inwardly projecting portions of the second set of bars for enclosing the motion-imparting means.

21. A cantilever thread-advancing reel supported from one end only thereof comprising a rotatable shaft, a flange-like member secured and keyed to the shaft, a set of spaced, longitudinally extending bar members carried by the flange-like member concentric with the shaft, a stationary sleeve about the shaft having eccentric external bearing portions thereon, flexible and resilient supporting means rotatably mounted on one of the eccentric bearing portions of the sleeve, a second set of spaced, longitudinally extending bar members interdigitating with those of the first set and each having an inwardly projecting portion fixedly secured to an outer portion of the supporting means, another portion of the eccentric bearing surface of the sleeve being arranged with its axis askew to the axis of the shaft, a rigid plate-like member mounted for rotation on the skew portion of the sleeve and having a portion arranged to co-operate with the bar members of the second set through rigid extensions from the inwardly projecting portions thereof, and sealing means having its outer portion secured to the flange-like member and an intermediate portion secured to the inwardly projecting portions of the second set of bars for enclosing the motion-imparting means.

12

22. Reel mechanism comprising a shaft, a set of spaced longitudinally extending bar members mounted concentrically about the shaft for rotation with respect thereto, two spaced supporting members substantially enclosing the space within said reel bars at each end thereof and thereby forming with the bars a rotatable cage-like housing, a second set of spaced, longitudinally extending members interdigitating with the members of the first set and having portions projecting inwardly of the cage-like housing, flexible and resilient means secured to the inwardly projecting portions and extending inwardly therefrom for supporting the second set rotatably about the shaft about an axis offset with respect to the center thereof, means for controllably flexing the resilient supporting means for imparting to a selected part of the second set of bar members at predetermined intervals a substantially axial reciprocatory motion relative to the first set of bar members, and flexible sealing means, extending substantially the entire length of the space inside the cage-like housing and having intermediate portions secured to the inwardly projecting portions of the second set of bar members, for enclosing the flexible and resilient supporting means and the motion-imparting means.

23. Reel mechanism comprising a shaft, a set of spaced longitudinally extending bar members mounted concentrically about the shaft for rotation with respect thereto, two spaced supporting members substantially enclosing the space within said reel bars at each end thereof and thereby forming with the bars a rotatable cage-like housing, a second set of spaced longitudinally extending members interdigitating with the members of the first set and having portions projecting inwardly of the cage-like housing, flexible and resilient means secured to the inwardly projecting portions and extending inwardly therefrom for supporting the second set rotatably about the shaft on an axis offset with respect to the center thereof, means for imparting to a selected part of the second set of bar members at predetermined intervals a substantially axial reciprocatory motion relative to the first set of bar members, said motion-imparting means comprising at least one member mounted for rotation with the bar members of the second set upon an axis askew to the axis of the bar members of the second set and arranged to co-operate with the bar members of the second set through rigid extensions from the inwardly projecting portions thereof, and flexible sealing means, extending substantially the entire length of the space inside the cage-like housing and having intermediate portions secured to the inwardly projecting portions of the second set of bar members, for enclosing the flexible and resilient supporting means and the motion-imparting means.
